UNITED STATES PATENT OFFICE.

CLARK W. HARRISON, OF CHICAGO, ILLINOIS.

DESIGN FOR A PAPER-KNIFE.

SPECIFICATION forming part of Design No. 24,144, dated March 26, 1895.

Application filed November 10, 1894. Serial No. 528,450. Term of patent 14 years.

To all whom it may concern:

Be it known that I, CLARK W. HARRISON, a citizen of the United States, residing at Chicago, in the county of Cook and State of Illinois, have invented and produced a new and original Design for Paper-Knives and the Like, of which the following is a specification, reference being had to the accompanying drawings, in which—

10 Figure 1 is a view of my design. Fig. 2 is a sectional view on line 2—2 Fig. 1.

The leading feature of my design consists in a handle *a* in the form of a cylinder having at one end a bead *b* and at the opposite 15 end an enlarged portion *c*, the blade *d* being

extended from the end of the handle upon which the enlarged portion *c* is provided. The blade narrows as it leaves the handle, expanding in width toward the middle of its length and then tapering symmetrically to a 20 point at the end.

What I claim is—

The design for a paper knife as herein shown and described.

In witness whereof I hereunto subscribe 25 my name this 1st day of November, A. D. 1894.

CLARK W. HARRISON.

Witnesses:

MICIAH WALKER,
W. CLYDE JONES.
